UNITED STATES PATENT OFFICE.

CHAUNCEY LEFLER, OF BENTLEY, MICHIGAN.

ELEVATOR.

1,411,736.

Specification of Letters Patent.

Patented Apr. 4, 1922.

Application filed June 30, 1921. Serial No. 481,540.

To all whom it may concern:

Be it known that I, CHAUNCEY LEFLER, a citizen of the United States, residing at Bentley, in the county of Bay, State of Michigan, have invented a new and useful Elevator; and I do hereby declare the following to be a full, clear, and exact description of the invention, such as will enable others skilled in the art to which it appertains to make and use the same.

The invention relates to elevators and has for its object to provide a manually operated elevator particularly adapted for use in connection with silos. Also to provide means whereby a counterbalanced horizontally disposed elevator platform may be held in various positions through the medium of pins carried by a centrally disposed pivoted rod extending through the platform and adapted to be partially rotated by the operator for positioning the pins beneath the platform.

A further object is to provide an elevator comprising a frame work having vertically movable therein a platform which is counterweighted and manually moved by an operator standing on the platform and grasping the pivoted rod extending through the platform substantially centrally thereof and provided with lugs adapted to engage the under face of the platform for holding the platform in raised position when raised to desired elevation.

With the above and other objects in view the invention resides in the combination and arrangement of parts as hereinafter set forth, shown in the drawings, described and claimed it being understood that changes in the precise embodiment of the invention may be made within the scope of what is claimed without departing from the spirit of the invention.

In the drawings:—

Figure 1 is a front elevation of the elevator showing the same disposed adjacent silo openings.

Figure 2 is a vertical sectional view through the elevator taken on line 2—2 of Figure 1.

Figure 3 is a horizontal sectional view taken on line 3—3 of Figure 2.

Figure 4 is a detail perspective view of one of the ends of the platform holding rod connections.

Referring to the drawings, the numeral 1 designates a conventional form of silo and

2 superimposed silo openings separated by sills 3. The silo is of the conventional form and it is to be understood that the openings 2 may be located as desired. Disposed adjacent the silo 1 and adjacent the openings 2 therein is a rectangular shaped frame 4 comprising forwardly disposed spaced guide members 5, which guide the elevator platform 6 in its upwardly and downward movement and rearwardly disposed uprights 7, which uprights are hollow and have vertically movable therein weights 8 to the upper ends of which are connected cables 9. Cables 9 extend upwardly and over pulleys 70 carried by the horizontally disposed shaft 11. The forward ends of the cables 9 pass over pulleys 12 carried adjacent the forward upper end of the frame 4 and then pass downwardly and are connected at 13 to 75 brackets 14 which extend upwardly from the sides of the platform 6. It will be seen that the weights 8 when properly proportioned will counterbalance the platform 6 when an operator is standing on the platform 6, and that the operator may easily through the medium of manual power raise the platform to the desired position, said platform being provided with members 15 which extend into guides 5^a of the guide members 5.

Extending vertically through an aperture 16 in the platform 6 is a rod 17 adapted to be grasped by the operator for moving the elevator platform 6 upwardly and downwardly. The upper end of the rod 17 is swivelly connected at 18 in a disc 19, which disc is carried by a hook 20 which engages in an eye 21 of an eye bolt 22 carried by a horizontally disposed beam 23. The 95 lower end of the rod 17 is similarly connected to a cross bar 24 at the lower end of the frame 4 and the same numerals apply to the connections as to the connections at the upper end of the rod 17.

By swivelly connecting the rod 17 it will be seen that the operator may easily rotate the rod at any time during the upward movement of the elevator, thereby allowing the lugs 25 carried by the rod 17 to be positioned at right angles to each other whereby the platform may be held in various raised positions by the engagement of the lower lugs 25 under the platform 6. The upper lugs 25 form means for preventing upward movement of the platform 6 according to various weights of different operators. Dur-

ing the raising operation the lugs 25 are positioned as shown in various figures, and in registration with the elongated apertures 16 in the platform 6. However during the platform holding operation the lugs are positioned substantially at a right angle position to that shown in the figures, and hence in positions where they will engage the upper or lower sides of the platform 6 according to the direction of movement of the platform.

From the above it will be seen that a manually operated elevator is provided which elevator is counter-weighted and so constructed that it may be held in various raised positions through the medium of lugs disposed above and below the platform and carried by a pivoted rod, within easy reach of the operator and also forming means whereby the operator may allow the platform to move upwardly under the impulse of the counterweights 8. It is to be understood that the counterweights are preferably of sufficient weight to raise the platform 6 when the operator is not standing on the same, therefore it will be seen that as the operator relieves the platform 6 of his own weight that the weights 8 will move the platform 6 upwardly.

30 The invention having been set forth what is claimed as new and useful is:—

1. The combination with a vertically movable weighted elevator platform, of means for holding said platform in various raised positions, said means comprising a vertically disposed rod extending through an aperture in the platform and pivotally mounted, and a plurality of pins carried by said vertically disposed rod and adapted to

be positioned by rotating the rod for engaging the under face of the platform and holding the same in raised position. 40

2. The combination with a vertically movable manually operated elevator platform, of means for holding said platform in various raised positions, said means comprising a vertically disposed rod extending through an elongated aperture in the platform and having its ends pivoted, and pins carried by said rod and adapted to be moved in a horizontal plane after they have passed through the aperture in the platform for engaging the under face of the platform and holding the same against downward movement. 45

3. The combination with a vertically movable manually operated elevator platform, of means for holding said platform against upward or downward movement when positioned in various raised positions, 60 said means comprising a vertically disposed rod extending through an elongated aperture in the platform and having its ends pivotally mounted, spaced pins carried by said rod and disposed in the same vertical plane, said pins being adapted to receive therebetween the platform and to be disposed at an angular position after the rod has been partially rotated for holding said platform against downward or upward movement. 65

In testimony whereof I have signed my name to this specification in the presence of two subscribing witnesses.

CHAUNCEY LEFLER
